The bands 1.1. chain 2, veined leaves 3.3. broad band 4, frame 5, veined figure 6, and scroll frame 7, are copied from Design designated as "Application 5³" for which Letters Patent were granted June 16th 1863, bearing the Patent Office Number 1771.

The improvement is as follows: In corner A is one fourth of a star enclosed by a frame of short lines and a chain of small balls. In corner B is one fourth of an oblong set figure resting on the diamond ground C, which has a scalloped border. The mottled work D, is attached to and nearly surrounds the scroll frame 7.

E, is a light frame work placed inside of the frame 5. The remainder of the design consists of a figured ground.
